[57] **CLAIM**

The ornamental design for a wall mounted emergency light unit, as shown and described.

DESCRIPTION

FIG. 1 is a top front perspective view of a wall mounted emergency lighting unit showing my new design;

FIG. 2 is a top plan view thereof on an enlarged scale;

FIG. 3 is a bottom plan view thereof on an enlarged scale;

FIG. 4 is a rear elevational view thereof on an enlarged scale;

FIG. 5 is a side elevational view thereof on an enlarged scale; the opposite side being a mirror image; and

FIG. 6 is a front elevational view thereof on an enlarged scale.

FIG. 1

FIG. 2

FIG. 3

FIG. 4

FIG. 5

FIG. 6
